UNITED STATES PATENT OFFICE.

JONATHAN S. GREEN, OF PITTSBURGH, PENNSYLVANIA, ASSIGNOR TO THE WESTING-HOUSE MACHINE COMPANY, A CORPORATION OF PENNSYLVANIA.

ELASTIC-FLUID TURBINE.

1,116,815.

Specification of Letters Patent. Patented Nov. 10, 1914.

Application filed March 28, 1914. Serial No. 827,892.

To all whom it may concern:

Be it known that I, JONATHAN S. GREEN, a citizen of the United States, and a resident of Pittsburgh, in the county of Allegheny and State of Pennsylvania, have made a new and useful Invention in Blade Construction for Elastic-Fluid Turbines, of which the following is a specification.

This invention relates to turbine blade construction and more especially to covers or shrouds therefor, and has for its object to provide a simple and reliable construction and one of minimum cost.

In the drawings accompanying this application and forming a part thereof: Fig. 1 is a view in perspective of a plurality of blades provided with covers or shrouds constructed in accordance with this invention; Fig. 2 is a view in perspective of a single blade machined for use in this construction; Fig. 3 is a view showing the face of a blade, the shroud or cover in cross section, and a spacing piece, such as utilized between adjacent blades, in section; and, Fig. 4 is a view in perspective of a portion of one-half of the cover or shroud used in this invention.

It will be understood that the invention is equally applicable to the stationary blades, generally termed vanes, of a turbine, although in the drawings I have illustrated it as applying to the rotary blades or buckets only, without any idea of limiting the invention to use with either.

In carrying out my invention I employ a shroud or cover for the outer ends of the blades, which comprises two separate members welded together after they are located in place on a row of assembled blades. By "welded" I mean united by the application of heat and pressure, or heat alone, as, for example, by means of autogenous soldering. I also provide shroud-engaging portions on the outer ends of the blades, which are adapted to be engaged by notches cut or otherwise formed in the engaging edges of the two shroud forming members. These shroud-engaging portions may be formed at or near the ends of the blades and may be of any suitable shape or of any size commensurate with the forces encountered by them.

In the illustrated embodiment of the invention a blade 5 of any desired cross section and formed in any desired manner,

either drawn or cast or drop forged, is milled near one end as shown at 6 so as to leave a rectangular connecting portion 7 joining the top and bottom portions of the blade. The blades may be secured in any suitable manner to the turbine element and, if desired, may be assembled into groups prior to assemblage in the turbine as shown in Fig. 1. In this view separate spacing members 8 lie between adjacent blades 5 and a wire or rod 9 passes through the spacing members and blades, the spacing members being provided with holes 10 to receive the rod or wire while the blades are provided with holes 11 for the same purpose.

A shroud or cover formed of two members 12 and 13 secures the outer or free ends of the blades together and, as shown, each of the members 12 and 13 is reduced in thickness along one of its edges as at 14 and notched as at 15. When the two members 12 and 13 are assembled to form a shroud or cover for a row of blades, the notches 15 of each member engage the shroud-holding portions formed on the blades or receive the connecting portions 7 of the blades, and the reduced portions of the members overlap, as is clearly shown in Fig. 3. The two members are positively locked to the blades on which they are mounted, by welding or spot-welding their engaging or overlapping portions together. This forms a rigid connection between the two members, and holds them firmly in position with relation to the shroud-holding portions formed on the blades, and consequently positively locks the shroud in place on the blades.

While I now believe it is preferable to notch one edge of each of the members 12 and 13 prior to locating them on the blades, and also to over-lap the notched edges of these members, one member only may be notched to receive the shroud-holding portions of the blades, and the two members may be welded together along their engaging edges, without being over-lapped.

It will, of course, be understood that the shroud or cover portion may be located in any position on the blades so that it will form a straight or a divergent passage for the fluid between the blades. It will also be understood that the means employed for securing the outer ends of the blades to-

gether and for holding them in their relatively proper positions, may be employed in connection with any blade-mounting means.

In accordance with the requirements of 5 the patent statutes, I have illustrated and described what I now consider to be the preferred embodiment of my invention, but it will be understood that various changes, substitutions, modifications, omissions and 10 additions may be made in the details of construction without departing from the spirit and scope of my invention as set forth in the appended claims.

What I claim is:

- 15 1. In a turbine, the combination of blades or buckets, and a cover or shroud compounded throughout its length, and having the separate parts welded together.
2. In a turbine, blades or buckets, and a 20 cover or shroud formed in two parts, overlapping throughout their length, and welded together along their engaging portions.
3. In a turbine, blades or buckets, and a 25 cover or shroud for the blades or buckets formed in two parts, each being provided with notches for engaging shroud-holding

portions formed on the blades, said two parts of said shroud being rigidly secured together by the application of heat thereto.

4. In a turbine, blades, a two-part cover 30 for said blades each part of which embraces the same blades and is secured to the other part by being welded thereto.

5. In a turbine, blades, a cover or shroud 35 for the blades formed in two parts, the parts being similarly provided along their engaging edges with coöperating blade-receiving notches, and being secured together by spot welding.

6. In a turbine, blades, a cover or shroud 40 for the blades formed in two parts and having overlapping notched edges welded together and engaging shroud-holding notches formed in the blades.

In testimony whereof, I have hereunto 45 subscribed my name this 26th day of March, 1914.

JNO. S. GREEN.
